CLAIM

The ornamental design of a high voltage motor, as shown and described.

DESCRIPTION

FIG. 1 is a front elevational view of a high voltage motor; FIG. 2 is a rear elevational view thereof; FIG. 3 is a top view thereof; FIG. 4 is a bottom view thereof; FIG. 5 is a right side view thereof; FIG. 6 is a left side view thereof; and, FIG. 7 is a perspective view thereof.

The broken lines shown in the drawings represent portions of the high voltage motor that form no part of the claimed design.
